R. H. PATTERSON.
WIRE FENCE STRETCHER.
APPLICATION FILED JUNE 26, 1919.

1,344,312.

Patented June 22, 1920.

Inventor
R. H. Patterson
Frank D. Hoy

UNITED STATES PATENT OFFICE.

ROBERT H. PATTERSON, OF WINCHESTER, KENTUCKY.

WIRE-FENCE STRETCHER.

1,344,312.

Specification of Letters Patent. Patented June 22, 1920.

Application filed June 26, 1919. Serial No. 306,910.

To all whom it may concern:

Be it known that I, ROBERT H. PATTERSON, a citizen of the United States, residing at Winchester, in the county of Clark and 5 State of Kentucky, have invented certain new and useful Improvements in Wire-Fence Stretchers; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

This invention relates to new and useful improvements in woven wire fence stretchers, and consists of a simple device of this character having various details of construction, combination and arrangement of parts 20 which will be hereinafter fully described shown in the accompanying drawings and then specifically defined in the appended claim.

25 My invention is illustrated in the accompanying drawings which, with the letters of reference marked thereon, form a part of this application, and in which:

Figure 1 is a perspective view showing 30 the application of my invention to a fence.

Fig. 2 is a detail view of the stretcher removed from the fence, and

Fig. 3 is a view showing a means for taking up the slack in the fence when held 35 by the stretcher.

Reference now being had to the details of the drawings by letter:

A designates a handle having a slot B formed in one end. A plate C is seated in 40 said slot and held therein by fastening means passed through registering apertures in the walls of the slot and said plate. It will be noted that said plate has serrations upon one end and which project, when the 45 plate is fastened in place, beyond one edge and the end respectively of the handle. It will also be noted that the meeting of the

teeth at the end and side have their points on the arc of a circle, so that the handle may be swung, so that the teeth will continue 50 to grip the post at the end of the handle, as will be readily understood.

A claw bar D is pivotally mounted upon the pin E passed through apertures in the opposite walls of the handle and has a 55 hooked end F for engagement with the fence to be stretched.

In Fig. 3 of the drawings I have shown a device for taking up the slack in the fence in the event of the latter being drawn taut 60 over a hollow or hill in the ground in which there is a slack in one side or the other. This device K has a slot or claw L at one end adapted to engage the slack edge of the fence and when given a twist will draw 65 the same taut.

The operation of my stretching device will be readily understood as the device is applied in the manner shown in the drawings. The peculiar arrangement of the 70 teeth upon the handle makes it possible to afford the device a continuous stretching action, as the handle is swung so that the teeth upon the side and end of the plate will engage a fence post. 75

What I claim to be new is:

A wire fence stretching device comprising a handle having an elongated slot in one end, a metallic member mounted in said slot and having its inner end seated against the 80 end of the slot, the walls of the latter and said member having registering apertures, and fastening means passing through the apertures, one longitudinal edge of said member and an end projecting respectively 85 beyond the longitudinal edge and end of the handle and serrated, the line of serrations about the end and corner being curved, a claw bar pivoted centrally to said handle adjacent to the inner end of said member. 90

In testimony whereof I hereunto affix my signature.

ROBERT H. PATTERSON.
